DOUCHE OR ENEMA DEVICE

Patricia Pendleton Bragg, Burbank, Calif.

Application December 2, 1955, Serial No. 550,623

1 Claim. (Cl. 128—248)

This invention relates to certain new and useful improvements in douche or enema devices and pertains particularly to a connection consisting of two parts which may be screwed together to form a cylindrical container for holding medicated discs, antiseptic soap, salt and the like. Said connection being adapted to be arranged or mounted between a water supply source and an injection discharge nozzle.

The apparatus may be attached directly to a single faucet for forcing a stream of water through said antiseptic containing device and to its discharge from the apparatus.

Another object is to provide a device of this character in which the parts will be of extremely simple construction, comprising a cylinder formed of two perforated sections which are screwed together and adapted to hold one or more discs of medicated material. A still further object is to generally improve and simplify the construction and operation of devices of this character and increase the efficiency thereof without increasing the cost of the same.

The invention consists in the details of construction and in the combination and arrangements of the several parts of my improved enema device whereby certain important advantages are attained and the device rendered simpler, less expensive and otherwise more convenient and advantageous for use, as will be hereinafter more fully described and claimed.

For a complete understanding of my invention, reference is to be had to the following description and accompanying drawings, in which,

Fig. 1 is a view in elevation of my improved device.

Fig. 2 is an enlarged longitudinal section of the device, the tubing at each end being shown in elevation with the free end thereof broken away.

Fig. 3 is a detail cross sectional view taken on the plane of line 3—3 Fig. 2 looking in the direction of the arrows and showing the perforations in the device.

Referring specifically to the drawings in which like numerals are used to designate like parts.

Numeral 2 is a flexible rubber tube connected by any suitable means at one end to a water supply such as a lavatory or bath tub faucet 3, and at the other end to an injection nozzle 4, which may be either an enema nozzle or a vaginal douche. The nozzle or douche is of the usual well known construction and is molded from a suitable thermoplastic composition such as vulcanized rubber or like plastic composition.

Obviously, applicant's invention is not in the faucet or discharge nozzle but is in the novel form of holder or device A for carrying the medicated discs or the like.

The device A is fitted within the flexible rubber tube 2 at any convenient point between the faucet 3 and the discharge nozzle 4.

2

The device A consists of two parts, B and C. The part B consists of a cylindrical portion provided with external threads 5. Connected to one side of the cylindrical portion and projecting therefrom is a reduced tubular portion 6 adapted to be fitted within one end of the rubber tube 2 and provided with corrugations 7 or roughened in the usual well known manner so as to be firmly attached to the tube 2 when assembled therein. On the face of the cylindrical portion and within the reduced tubular portion is a series of holes 8 which permit the water to pass through the cylindrical portion which carries one or more medicated discs E.

The part C also consists of a cylindrical portion provided with internal threads 9 adapted to mesh with the external threads 5 to lock together the sections B and C.

The section C is also provided with a reduced tubular portion 10 adapted to be fitted within the other end of the rubber tube 2 and provided with corrugations 11 or roughened in the usual well known manner so as to be firmly attached to the tube 2 when assembled therein.

The cylindrical part C is also provided with a series of holes 12 which permit the water to pass from the medicated discs E to the discharge nozzle 4.

To render the device absolutely water tight a small washer F of rubber or other suitable material may be placed in position within the cylindrical part C. The operation is quite simple. After the sections B and C are fitted within the ends of the tube 2, the operator places one or more medicated discs within the section B which is held in the left hand; then with the right hand the section C is screwed firmly to the section B and the device is ready for use.

The device is designed primarily to be used as a vaginal douche but it is obvious that it also could be used as an enema by using tablets of salt or soap instead of the medicated discs.

The device could also be used by using only warm water for instance, in the treatment of prostate enlargement.

By this device, treatment could be applied to the prostate very directly through the rectum. The rectal douche does not mean the flushing of the entire colon. It is sufficient to confine it to the rectum and it is best to use the hot water in the form of irrigation, letting it run out as fast as it enters for 2 or 3 minutes or more. Such irrigation with hot water has a very soothing effect when the prostate is in an irritable and inflamed condition.

While I have illustrated and described in detail preferred embodiments of the invention, it is thought to be obvious that a device constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangements and formation of the several parts herein shown in carrying out my invention in practice except as hereinafter claimed.

I claim:

A device of the class described comprising a flexible fluid conducting member adapted to be connected at one end to a suitable source of liquid supply, a cylindrical medicated disc container consisting of two cylindrical parts, the first part being threaded on its outside cylindrical surface and having a roughened tubular portion of reduced diameter adapted to be fitted within the other

end of the flexible fluid conducting member, a series of holes on the face of the cylindrical part within the reduced tubular portion, the second cylindrical part being threaded in its inside cylindrical surface and having a roughened tubular portion of reduced diameter adapted to be fitted within the end of a rubber tube the other end of said tube being connected to a discharge nozzle, a series of holes on the face of the second cylindrical part within the reduced tubular portion said second part being adapted to be firmly screwed into the first part, whereby a closed
